H. FIETSCH, JR.
MOISTURE PROOF PAPER PACKAGE OR CARTON.
APPLICATION FILED MAY 26, 1910.

1,269,918.

Patented June 18, 1918.

UNITED STATES PATENT OFFICE.

HERMAN FIETSCH, JR., OF CHICAGO, ILLINOIS, ASSIGNOR OF ONE-HALF TO RUECKHEIM BROS. & ECKSTEIN, OF CHICAGO, ILLINOIS, A CORPORATION OF WEST VIRGINIA.

MOISTURE-PROOF PAPER PACKAGE OR CARTON.

1,269,918.

Specification of Letters Patent. Patented June 18, 1918.

Application filed May 26, 1910. Serial No. 563,510.

To all whom it may concern:

Be it known that I, HERMAN FIETSCH, Jr., a citizen of the United States, and a resident of Chicago, county of Cook, and State of Illinois, have invented certain new and useful Improvements in Moisture-Proof Paper Packages or Cartons, of which the following is a description.

10 The invention relates to foldable, moisture-proof paper packages or cartons for marketing chemicals, soap powder, cereals, crackers and other goods which deteriorate either by losing or absorbing moisture on exposure to the atmosphere.

15 It is customary to coat the paper box board from which such cartons are made with paraffin wax or other waterproofing material, but in such cases, the overlapping portions of the carton and the foldable flap

20 or cover portions cannot be sealed tight since the coat of waterproofing material prevents the adhesion of glue, paste or like cementing material. In the common form of collapsible carton made of a blank of stiff

25 paper board cut and scored to form the corners and foldable flaps, the presence of a surface coat of waterproofing material prevents the sealing of the overlapping seams and flaps. These overlapping parts are usu-

30 ally held together by suitable tucks or tongues, but the carton is not thereby rendered moisture tight at such points. Moreover, any coat of waterproof material will interfere if not entirely prevent the application of printed matter and of colors to the

35 surface of the carton, and, in order that the package may present an attractive appearance, it is customary to inclose the carton in a supplemental, outer wrapper.

40 In accordance with the present invention, the paper package or carton is formed of a stiff paper box-board comprising layers of suitable paper stock united by an intermediate layer of oxidized petroleum residuum.

45 This waterproof material is usually formed by blasting petroleum residuum or tailings with air at high temperature. It is applied in melted or fused condition between the layers of paper stock which are then pressed

50 together by passing the same between rollers or in any other suitable manner. The paper box-board thus made is then cut and scored to form the carton. The oxidized petroleum residuum forms a thin, pliant, waterproofing

layer which firmly unites the layers of paper stock, but does not penetrate the same to any appreciable extent, and the surface of the carton is free to receive glue or paste at the overlapping parts to thereby completely inclose the goods and render the package moisture-proof at all points. Moreover, its inner surface is free from material which might contaminate the contained goods.

In the accompanying drawing which illustrates the form of carton to which the invention is more particularly directed, Figure 1 is a view of the blank from which the carton is formed. Fig. 2 is a perspective view of the collapsed carton. Fig. 3 is a perspective view of the carton opened out to receive the charge. Fig. 4 is a perspective view of the completed package and Fig. 5 is a cross-section of the same.

The stiff paper box-board is formed of inner and outer layers of suitable paper stock. 75 The outer layer preferably comprises paper box-board *a* having an outer surfacing *b* of Manila or other suitable paper pasted thereon. The inner layer *c* is formed of Manila or other suitable paper or of paper box-board. The oxidized petroleum residuum, which forms a thin intermediate layer *d* between the layers of paper stock, is applied in melted or fused condition and the whole is then subjected to pressure, preferably, by 85 passing the same between rollers.

The resultant waterproof board is then cut into blanks, such, for example, as shown in Fig. 1. This blank is scored on the lines 1 to form the corners or folds at the edges 90 of the sides of the carton and is cut on the lines 2 to form foldable end flaps *e*. A flap *f* at one side edge of the blank is lapped over and glued to the opposite side edge to form a tight seam extending lengthwise of the 95 carton. The collapsed carton thus formed is shown in Fig. 2. To fill the carton, it is opened out as shown in Fig. 3, and after the flaps *e* at one end have been folded upon one another and securely glued together, the 100 goods are placed therein and the flaps at the opposite end are folded and glued together to form the finished package (see Fig. 4) and completely inclose the goods.

The thickness of the layers of paper stocks 105 employed may vary in accordance with the desired thickness of the walls of the carton. The waterproofing layer *d* of oxidized pe-

2

troleum residuum need only be a few thousandths of an inch in thickness. This substance melts at the high temperature of about 210° to 240° Fahrenheit and the waterproof layer *d* will not therefore tend to liquefy and run or exude from between the layers of paper stock under the influence of heat to which the packages may be exposed. It has no offensive odor such as might contaminate the inclosed goods. Moreover, while the waterproofing layer *d* of this material firmly unites the layers of paper stock, it does not penetrate the same. The surface of the carton is thus free to receive glue or other suitable cement at the side seam *f* and at the foldable flap portions *e*, and the package is moisture-proof, not only in its body portion, but at the overlapping parts as well to effectively protect the inclosed goods. The surface of the carton is also free to receive ink and coloring material and may be printed upon and decorated in any desired manner. Moreover, inasmuch as the package is moisture-proof at all points, it can be used for goods containing a large amount of moisture, or for deliquescent material, and the printed and decorating matter on its surface will remain intact and will not become discolored or disfigured. The layer *d* of this waterproof material is tough and pliant and is not ruptured by the scoring and bending of the stiff paper box-board at the corners of the carton, and these qualities are retained under the wide

ranges of temperature to which the packages 35 may be exposed.

It is obvious that the details of construction set forth may be varied without departure from the essentials of the invention as defined in the claims. 40

I claim as my invention:—

1. A collapsible, moisture proof carton comprising side walls and foldable end flaps, said side walls being connected to one another and to said end flaps by corner folds 45 and said walls and flaps being formed of layers of paper stock, and an intermediate, thin, pliant layer of a waterproof fused cement uniting the layers of paper stock and extending without interruption through said 50 corner folds, substantially as described.

2. A collapsible, moisture proof carton comprising side walls and foldable end flaps, said side walls being connected together and to said end flaps by integral corner folds 55 and said walls and flaps being formed of layers of paper stock and an intermediate, thin, pliant layer of a fused cement uniting but not penetrating the layers of paper stock and extending throughout said side walls and said foldable end flaps and without interruption through said connecting corner folds, substantially as described. 60
